UNITED STATES PATENT OFFICE.

PARKER WINEMAN, OF CHICAGO, ILLINOIS.

APPARATUS FOR PREVENTING BLOW-HOLES IN CASTINGS.

1,161,101.

Specification of Letters Patent.

Patented Nov. 23, 1915.

Application filed February 24, 1914. Serial No. 820,723.

To all whom it may concern:

Be it known that I, PARKER WINEMAN, a citizen of the United States, and residing at Chicago, Cook county, Illinois, have invented certain new and useful Apparatus for Preventing Blow-Holes in Castings, of which the following, taken in connection with the drawing, is a description.

My invention has for its object the production of apparatus to be used in connection with a flask of usual construction, into which sand is rammed upon a contained pattern to form a mold, in which and during the operation of pouring the hot metal, the air and gases are drawn therefrom, so that the finished product is free from honey-combs or blow-holes, which is a very common defect as castings are made at the present time, and a cause of much annoyance and expense in their production.

Heretofore it has been customary to puncture the sand with a steel wire of sufficient size extending from the top to the mold or imprint, and from the sides to the imprint, to vent for the escape of air or gas accumulated therein, also other openings or risers are made extending through the sand to the imprint through which a portion of the hot air and gases escape to atmosphere as the mold is filled with hot metal. This method, however, has not been sufficient to prevent the honey-combing of the metal in the castings, especially in steel castings, and very frequently in gray-iron castings, as well as other metals.

The principal cause of the defects referred to arises from the gas generated while the molten metal is being poured into the imprint, as it reaches the damp sand. The method above referred to and heretofore employed for venting, is inadequate for the escape of gas and hot air, and in the process the metal is retarded in its inflow into all parts of the imprint in consequence of which the gas, hot air, and atmospheric pressure, amounting to approximately 14 pounds per quarter inch, all of which retards the inflow of the metal to all parts of the imprint, and thus the gas, hot air and atmospheric pressure acting against the flow of the metal prevents a free and sufficient escape of the gas and tends to force it into remote pockets, angles, corners, etc., where it is trapped and more or less of it retained in the metal while it is cooling, thus forming the blow-holes and honey-combs which are decided defects in all

castings. This condition is most prevalent where there is shrinkage, and in points where the metal must rise above the highest point of the pattern where the metal is being poured into the mold in which case the air and gas remain with no vent through which to escape.

By the use of my construction, in combination with a well known process of creating a vacuum, the gas and hot air together with the pressure of the atmosphere being removed, the time spent in probing to vent will be saved. the inflow of the metal will be increased and the defects will be reduced to a minimum, and by removing the cause of the defects the result is a perfect product. To accomplish this result I provide a mold wherein I create a vacuum (or as near a vacuum as is possible) and withdraw all the gas and hot air relieving the mold or imprint of air pressure by eliminating the gaseous products as fast as they are generated while the molten metal is being poured into the imprint, this is done with the exhaust fan and my construction.

In the accompanying drawings I have illustrated what I now consider the preferred form of a construction adapted to carry out my invention and accomplish the results above set forth, and in these drawings—

Figure 1 is a top plan view of a flask or mold, with one-half the cover broken away; and Fig. 2 is a longitudinal sectional view taken on line 2, 2 of Fig. 1.

In reducing my invention to practice I employ a mold or a flask of two parts A, A' of the kind now in ordinary use having mold boards in the bottom thereof. In this flask is placed the sand to form the desired mold.

In the drawing I have illustrated a wheel B as the pattern being used to describe my invention. When the flask is filled with sand a groove a' is formed around or partially around the pattern any distance therefrom desired. This groove may be made by hand or by a pattern pressed into the sand.

Extending into the sand from the groove a' are ports a a any number necessary, through which the air or gas is drawn from the mold and out through the exhaust as hereinafter described. These ports reach in depth approximately to the bottom line of the pattern B and open into the groove a' at the top of the sand as shown.

When the top of the flask is in position

ports a^2 , a^2 , extend to the grooves or recesses a' , a' . These ports a^2 may be made by a pattern or by probing. C, C, are exhaust cups inverted on top of the sand in the flask and pressed downwardly into the sand a sufficient distance to form an air-tight chamber into which the ports a^2 exhaust, or into which the gas or air is drawn. Extending from said cups to the pattern B

10 are the ports D, D.

Extending from the cups C, C, to the vent pipe D' are pipes c, c, which are preferably flexible. The vent pipe D' is a short pipe, and connected through and with the pipe 15 D², which may be made in sections and adapted to be fitted to the pipe D' in any desired manner. The pipe D² has connection with a suction fan D³ located at any convenient place about the building. This 20 suction fan is of any well known type of construction and details thereof will not be here given. This fan is used to create a vacuum (or partial vacuum) and is driven by a belt or motor in the ordinary manner. 25 In the use of a device of this kind I prefer to have a main overhead pipe provided with an exhaust fan at one end thereof which will be sufficiently powerful to serve a large number of molders, each flask being provided with a vent pipe extending to the main over-head pipe D². From the overhead pipe D² any number of flexible pipes may be connected and extended to the flask. With the use of this construction, when the 30 molten metal is poured into the mold, the hot air and gas arising therefrom are drawn through the different ports a, a², and D, to the exhaust cups C, C, thereby at once relieving atmospheric pressure.

40 One of the advantages in the use of this invention, in addition to the advantages already pointed out, is that all air and gas arising from the molten metal passes through the pipes and is vented to atmosphere outside the building, so that none can escape in the shop or foundry to the detriment of the employees.

In the drawings I have illustrated only the principal objects of my invention, which 50 as will be obvious, may be carried out in different ways, and I wish to be understood as contemplating different arrangements of the ports to exhaust from different parts of

the mold, also that more exhaust cups and different shapes suitable for the casting may 55 be used if found desirable, also that the pipe connections may be changed.

In the use of this construction the cups C, C, are simply pressed into the sand which forms an air-tight chamber, the cups being 60 held in position by atmospheric pressure.

I claim:

1. In an apparatus of the class described, a molding flask containing prepared sand having ports provided therein at predetermined intervals, and means for drawing through said ports while the same is being filled, all the gases generated by the hot molten metal arising on the inner surface of the mold. 70

2. In an apparatus of the class described, a molding flask containing prepared sand having ports provided therein at predetermined intervals, inverted receptacles of any form communicating with said ports, 75 and a means for withdrawing through said ports gases arising from the hot molten metal on the surface of the mold while the same is being filled with molten metal.

3. In an apparatus of the class described, 80 a molding flask containing prepared sand having ports leading to the mold provided therein at predetermined intervals, inverted receptacles registering with said ports, vent pipes connecting with said receptacles, and means operating through said pipes to withdraw the gas generating from the damp prepared sand comprising the mold as the hot molten metal is rising in the mold. 85

4. In an apparatus of the class described, 90 the combination of a plurality of flasks containing prepared sand and having ports extending into proximity to the mold or imprint, inverted receptacles registering with said ports, a suction apparatus and pipes 95 connecting said apparatus with different receptacles through which the gas created is withdrawn.

In testimony whereof I have signed this specification in the presence of two subscribing witnesses.

PARKER WINEMAN.
